a corporation

Application March 8, 1946, Serial No. 652,851

22 Claims. (Cl. 139—391)

1

The present invention relates to textile pile fabrics and method for making same, and particularly to carpets and rugs having decorative designs formed in relief on the face of the fabric.

An object of this invention is to provide an improved and novel method for making pile fabrics of the character mentioned, whereby a three tone effect is obtained in a carpet, using but a single color yarn as pile material.

Another object hereof is to provide a novel and improved three tone carpet having pile areas of different character though all pile material is the same and of one color.

A further object of the present invention is to provide a novel and improved carpet construction and method for making same, which requires no change in present carpet making machinery, is economical, practical and effective in producing the desired result as described.

Other objects and advantages will become apparent as this disclosure proceeds.

In the accompanying drawings forming part of this specification, similar characters of reference indicate corresponding parts in all the views.

Fig. 1 shows pictorially, the pile surface of a carpet made in accordance with the teachings of this invention, presenting a three tone effect.

Fig. 2 is a diagrammatic view showing in elevation, the pile structure for surface areas of said carpet, which present one of the color tones.

Fig. 3 is a similar view of pile structure for surfaces, areas of said carpet, for presenting another color tone.

Fig. 4 is a similar view of the pile structure used for surfaces areas of said carpet, which present a third color tone.

In the manufacture of pile fabrics, the manner and equipment in use with the Jacquard loom for making rows of pile of high loops, low loops, cut to form tufts or left uncut, as well as the raising of double strands of pile yarn to form dense pile rows, and raising pile in only alternate rows, leaving the intermediate rows without pile being formed therealong, are all known. I will therefore proceed with a description of the character of the pile as used in the practice of this invention.

It is important to note, that for making the pile, a single kind of material of a single color is used for the entire pile surface of the carpet.

Two sets of wires are used on the loom for raising pile loops. One set having knives for cutting the loops, are placed relatively high and in alternate relation with the second set of wires which are relatively low. The low wires have no knives.

The pile areas marked "A" are obtained by having double strands of pile yarn raised by the loom on the low wires; no pile being raised in this in-

2

stance on the high wires. The density of the pile yarn and the closeness of weave, causes the low pile loops thus formed to overlap the empty rows.

The pile areas marked "B" are obtained by having double strands of pile yarn raised by the loom on the high wires; no pile being raised in this instance on the low wires. When said high wires are withdrawn, as known in the art, such high loops are cut to form tuft which splay; thus covering the intermediate rows in which no pile had been raised.

The pile areas marked "C" are obtained by having double strands of pile yarn raised by the loom on the low wires, and single strands on the high wires. Upon withdrawal of the wires, the high loops are cut. In such areas "C," the cut high loops which are now termed tufts, will cause a shadow to fall on the relatively dense uncut low loops.

In the drawings, the numeral 15 designates the low uncut loops, the numeral 16 designates the tuft of two strands each formed after the high pile loops are cut, and the numeral 17 designates the rows where no pile material is raised.

Adjacent rows as mentioned herein shall be deemed the consecutive rows as performed in weaving operations on the loom.

The appearance of the respective pile areas will be different, and though the pile material used is the same for all areas and but of one color, the resulting entity will be a three tone carpet as can be observed in Fig. 1 which is a photographic showing of such carpet.

This invention is capable of numerous forms and various applications without departing from the essential features herein disclosed. It is therefore intended and desired that the specific description herein be deemed illustrative and not restrictive and that the patent shall cover all patentable novelty herein set forth; reference being had to the following claims rather than to the particular showing herein to indicate the scope of this invention.

45 I claim:

1. A three tone pile fabric having on one of its surfaces, adjacent first, second and third tone areas; the first tone area comprising rows free of pile material and rows of uncut pile loops, in alternate relation; the loops of successive pile rows of the first tone area being in contact; the second tone area comprising rows free of pile material and rows of tufts of few strands each, in alternate relation; the tufts of successive pile rows of the second tone area being in contact; the third tone area comprising rows of uncut pile loops and rows of tufts of few strands each, in alternate relation; all pile tufts being relatively high; all uncut pile loops being relatively low; all successive rows of the respective tone areas being

adjacent each other and all pile material being of a single color.

2. A three tone pile fabric having on one of its surfaces, adjacent first, second and third tone areas; the first tone area comprising rows free of pile material and rows of relatively low uncut pile loops, in alternate relation; the loops of successive pile rows of the first tone area being in contact; the second tone area comprising rows free of pile material and rows of relatively high cut pile loops, in alternate relation; the cut pile loops of successive pile rows of the second tone area being in contact; the third tone area comprising rows of relatively low uncut pile loops and rows of relatively high cut pile loops, in alternate relation; all successive rows of the respective tone areas being adjacent each other and all pile material being of a single color.

3. A three tone pile fabric having on one of its surfaces, adjacent first, second and third tone areas; the first tone area comprising rows of uncut pile loops; the loops of successive pile rows of the first tone area being in contact; the second tone area comprising rows of tufts; the tufts of successive pile rows of the second tone area being in contact; the third tone area comprising rows of uncut pile loops and rows of tufts of few strands each, in alternate relation; all successive rows of the respective tone areas being adjacent each other; all pile tufts being relatively high; all uncut pile loops being relatively low and all pile material being of a single color.

4. A three tone pile fabric having on one of its surfaces, adjacent first, second and third tone areas; the first tone area comprising rows of uncut pile loops; the loops of successive pile rows of the first tone area being in contact; the second tone area comprising rows of cut pile loops; the cut pile loops of successive pile rows of the second tone area being in contact; the third tone area comprising rows of uncut pile loops and rows of cut pile loops, in alternate relation; all successive rows of the respective tone areas being adjacent each other; all cut pile loops being relatively high; all uncut pile loops being relatively low and all pile material being of a single color.

5. A three tone pile fabric as defined in claim 1, wherein the rows of tufts in the third tone area are respectively less dense than all the other pile rows of all the tone areas.

6. A three tone pile fabric as defined in claim 2, wherein the rows of cut pile loops in the third tone area are respectively less dense than all the other pile rows of all the tone areas.

7. A three tone pile fabric as defined in claim 3, wherein the rows of tufts in the third tone area are respectively less dense than all the other pile rows of all the tone areas.

8. A three tone pile fabric as defined in claim 4, wherein the rows of cut pile loops in the third tone area are respectively less dense than all the other pile rows of all the tone areas.

9. A three tone pile fabric as defined in claim 1, wherein the rows of tufts in the third tone area are relatively less dense than the rows of uncut pile loops in said tone area.

10. A three tone pile fabric as defined in claim 2, wherein the rows of cut pile loops in the third tone area are respectively less dense than the rows of uncut pile loops in said tone area.

11. A three tone pile fabric as defined in claim

3, wherein the rows of tufts in the third tone area are relatively less dense than the rows of uncut pile loops in said tone area.

12. A three tone pile fabric as defined in claim 4, wherein the rows of cut pile loops in the third tone area are respectively less dense than the rows of uncut pile loops in said tone area.

13. A three tone pile fabric as defined in claim 1, wherein all pile material is identical in all the tone areas.

14. A three tone pile fabric as defined in claim 2, wherein all pile material is identical in all the tone areas.

15. A three tone pile fabric as defined in claim 3, wherein all pile material is identical in all the tone areas.

16. A three tone pile fabric as defined in claim 4, wherein all pile material is identical in all the tone areas.

17. The method of making a three tone pile fabric which consists of weaving a first tone area comprising rows free of pile material and rows of relatively low pile loops, in alternate relation, whereby loops of successive pile rows of said first tone area are in contact; then weaving a second tone area with pile material of the same color as used for the pile rows in the first tone area, comprising rows free of pile material and rows of relatively high pile loops, in alternate relation, whereby loops of successive pile rows of said second tone area are in contact; then weaving a third tone area with pile material of said same color, comprising rows of relatively low pile loops and rows of relatively high pile loops, in alternate relation; said weaving being done so that the respective tone areas are in adjacent relation, and then cutting the relatively high pile loops at substantially their highest points.

18. The method of making a three tone pile fabric which consists of weaving a first tone area comprising rows of relatively low pile loops, whereby loops of successive pile rows of said first tone area are in contact; then weaving a second tone area with pile material of the same color as used for the pile rows of the first tone area, comprising rows of relatively high pile loops, whereby loops of successive pile rows of said second tone area are in contact; then weaving a third tone area with pile material of the said same color, comprising rows of relatively high pile loops and rows of relatively low pile loops, in alternate relation; said weaving being done so that the respective tone areas are in adjacent relation, and then cutting the relatively high pile loops.

19. The method as defined in claim 17 wherein the rows of high pile loops in the third tone area are woven less dense than all the other pile rows of all the tone areas.

20. The method as defined in claim 18, wherein the rows of high pile loops in the third tone area are woven less dense than all the other pile rows of all the tone areas.

21. The method as defined in claim 17, wherein the rows of high pile loops in the third tone area are woven less dense than the rows of low pile loops in said area.

22. The method as defined in claim 18, wherein the rows of high pile loops in the third tone area are woven less dense than the rows of low pile loops in said area.
